VOLTAGE TESTER CASING

James E. Winfrey, Asheville, and Wallace Hoyt Orr,
Hendersonville, N.C., assignors to Square D Company,
Park Ridge, Ill.

Filed Mar. 8, 1971, Ser. No. 122,263

Term of patent 14 years

Int. Cl. D10—05

U.S. Cl. D26—1

FIG. 1

FIG. 4

FIG. 2

FIG. 3

FIG. 5

FIG. 6

FIG. 1 is an isometric view of a voltage tester casing showing our new design;

FIG. 2 is a front elevational view thereof;

FIG. 3 is a side elevational view thereof;

FIG. 4 is a top elevational view thereof;

FIG. 5 is an isometric view of another form of our new design wherein shallow, elongated grooves appear at the front and side surfaces thereof; and

FIG. 6 is an isometric view of yet another form of our new design wherein a plurality of openings appear in a recessed front surface thereof.

The rear of the voltage tester casting is essentially plain and without ornamentation.

We claim:

The ornamental design for a voltage tester casing, substantially as shown and described.
